METHOD OF AND MEANS FOR MAKING
ARTIFICIAL SNOW

David H. Crosser, Chicago, Ill.

Application November 12, 1943, Serial No. 510,079

6 Claims.

(Cl. 18—1)

Powdered soap or soap flakes can be mixed with water and beaten into a light, fluffy mass which, upon drying, is very light and porous and structurally strong. Not only is the material light in weight but it is as white as snow and makes an admirable artificial snow when divided into small masses and dried.

The object of the present invention is to enable anyone to create great numbers of such little masses, quickly and easily, and to apply them in a wet state, haphazardly and without being constrained in any way after being created, to an object to be decorated.

In carrying out my invention, I place a large mass of the fluffy material in a bag or the like having a stiff, perforated part through which the material may be extruded. The bag is then squeezed to cause the fluffy soap to exude at the perforations. After the soap has been extruded to the desired extent the little protruding masses are separated from the main body and are hurled toward their destinations.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a side view of a preferred embodiment of the invention, a fragment being broken away and the striker being shown in two positions, in full and broken lines, respectively; Fig. 2 is a view looking at the upper end of the device, as it appears in Fig. 1, from a point toward the right thereof; Fig. 3 is a view, on a larger scale, of the stiff receptacle that is at the top in Fig. 1; Fig. 4 is a section on line 4—4 of Fig. 3; Figs. 5 and 6 are views like Fig. 1, showing only the stiff receptacle, some soapy material having been extruded in Fig. 5 and the extruded little masses having been discharged in Fig. 6; Fig. 7 and Fig. 8 are views corresponding to Fig. 1 and Fig. 2, respectively, illustrating another form of the invention; Fig. 9 is a top plan view of the device appearing in Fig. 7, the flexible sleeve or bag being omitted; Fig. 10 is a section on line 10—10 of Fig. 7; and Figs. 11 and 12 are sections, on a larger scale, on line 12—12 of Fig. 10, showing in the one soapy material partially extruded and in the other, the condition existing just after the extruded little masses leave the device for their intended destinations.

I have discovered that while it is easy to extrude soapy material of the desired consistency through perforations in the bottom of a can or other receptacle, it is quite another matter to secure little masses that look like snowflakes and

apply them effectively to a Christmas tree or other object. This problem I have solved by finding that after little plugs of soapy material have been extruded, they may simultaneously be separated from the receptacle and started on their way by striking a sharp blow against the receptacle. The cross sectional areas and shapes of the plugs depends on the sizes and shapes of the perforations which, of course, are fixed, but the lengths of the plugs may be varied at will.

A simple form of apparatus for carrying out my invention comprises a cup-shaped receptacle such as indicated at 1 in Figs. 1 to 6; the bottom of the receptacle containing numerous holes 2. Good results have been obtained with holes that are about $\frac{1}{4}$ " square, round holes about $\frac{1}{4}$ " in diameter, and triangular holes the sides of which measure about $\frac{1}{4}$ ". A mixture of holes of different sizes and shapes permits a very natural snow effect to be achieved. In order that a large quantity of snow may be made from a single batch of soap material, I attach to the open end of the receptacle a long flexible sleeve 3 of cloth or other suitable material.

In using the device, the receptacle and the sleeve continuation thereof are filled with the wet, creamy soap; the free end of the sleeve is closed, either by gripping it in one hand, or otherwise; and the sleeve is then squeezed, as in the case of a tube of toothpaste, until plugs or strings of soap exude from the bottom of the receptacle. A sharp blow is then struck against the side of the receptacle, causing the extruded little soap masses, indicated at B in Fig. 5, to be severed from the main mass A and to be flung or hurled away as indicated in Fig. 6. By holding the device over a part of a Christmas tree, for example, and at some distance therefrom, at the time a blow is struck, the rudimentary artificial snow flakes will be distributed nicely, either thickly or sparsely, as desired. When the little soap masses land, they flow more or less, causing them partially to surround the twigs on which they are to remain and to droop so as to bear little resemblance to the shapes which they originally had. After one group of extruded portions has been discharged, the sleeve or bag may immediately be given another squeeze and the process of extrusion and delivery be repeated. In a very short time a whole Christmas tree may be covered with a non-inflammable artificial snow which, upon drying, is sufficiently firm to endure without deterioration throughout the holiday season.

The operation of the device is made easier by providing the device with a suitable handle for holding it positively and firmly in any desired position at the time of ejecting the rudimentary artificial flakes. In the arrangement shown, the handle is simply a long, round stick 4 extend-

ing axially of the device from the bottom of the receptacle through the sleeve and projecting beyond the free end of the latter to provide a hand hold. The stick and the receptacle may be fastened together by a screw 5 passing through the bottom of the latter and into the stick. While the required blows may be struck by the hand or by some object held in the hand for that purpose, it will usually be found to be advantageous to mount a suitable striker on the device. In the arrangement shown, I provide a hammer member 6, pivotally mounted on ears 7 on the side of the receptacle for rocking movements in a radial plane. A spring 8 normally holds the hammer head against the side of the receptacle close to the bottom. When a thumb or finger is pressed against the tail end of the hammer to swing the head away from the receptacle as indicated in broken lines in Fig. 1, the tension in the spring is increased. Therefore, when the hammer is released, the head thereof is driven sharply against the side of the receptacle. With this construction the user need simply fill the device, tie the sleeve shut with a string 9, to close its free end, and then may proceed to make artificial snow as rapidly as he can alternately squeeze the sleeve and snap the hammer.

In Figs. 7 to 12 the additions to the basic combination of the perforated receptacle and flexible sleeve or bag are somewhat different from those just described. The handle, for example, is a wire member bent into the form of a ring 10 engaged with the bottom of the receptacle and secured thereto by soldering or otherwise. The two ends of the wire are bent outwardly to produce two radial legs 11 that are entered into one end of a suitable handle 12 to be gripped in one's hand.

All of the holes 14 lie on one side of a diameter of the receptacle bottom. Within the receptacle is a vane or flap 15 hinged to a little bracket 16 fastened to the unperforated half of the receptacle bottom. A spring 17 tends constantly to hold the vane or flap against the inner face of the perforated portion of the receptacle bottom. The cylindrical wall of the receptacle contains a longitudinal slot 18 through which extends a finger piece 19, fixed to the vane or flap. The vane or flap contains holes 20 that are staggered with respect to the holes 14.

With this construction, the device being filled with the soap material, the user takes hold of the handle and, with his thumb, presses the finger piece 19 from the position indicated in Fig. 7 or Fig. 12 into that shown in Fig. 11, thereby uncovering the holes in the bottom of the receptacle. Then, when the sleeve is squeezed, soap material is pushed out of the latter holes, if that is desired. When the finger piece is released, the vane or flap snaps against the bottom of the receptacle, hurling the extruded small soap masses away from the device. In moving toward the bottom of the receptacle the vane or flap drives some of the soap ahead of it and thus causes larger masses to be extruded than those resulting solely from the squeezing of the sleeve. If the flap is allowed to rest against the bottom of the receptacle while the sleeve is squeezed merely to insure that the receptacle is filled, the subsequent operation and release of the finger

piece will not only drive the little soap masses away but will first actually extrude them. This last method of operation results in fairly uniform soap bodies delivered at any hole throughout a series of successive operations; whereas, when the flap is held back while the bag or sleeve is being squeezed, the size of the extruded masses may be varied within wide limits.

While I have illustrated and described with particularity only a few of the many possible modifications of my invention, I do not desire to be limited to the exact structural details thus illustrated and described; but intend to cover all methods, forms and arrangements which come within the definitions of my invention constituting the appended claims.

I claim:

1. The method of producing and applying artificial snow which consists in forming a damp, 20 fluffy mass of soap, forcing the soap into a stiff receptacle having a wall provided with numerous perforations to extrude it through the perforations, and then striking a sharp blow against the receptacle to jar all of the extruded small masses of soap loose and cause them to be driven away from the receptacle and scattered.

2. A device for producing artificial snow from soap, comprising a stiff open-top receptacle having a perforated bottom, a long flexible sleeve secured to the open end of the receptacle and forming an extension thereof, a handle attached to the receptacle and serving to support the device when gripped by a user in operating the device, and means to strike the receptacle to jar the same and cause all extruded masses of soap to be broken off simultaneously and to be driven away from the perforated bottom of the receptacle.

3. A device for producing artificial snow from soap, comprising an open-top receptacle having a perforated bottom, a long flexible sleeve secured to the open end of the receptacle and constituting an extension thereof, a handle attached to the receptacle and serving to support the device when gripped by a user in the operation of the device, and a spring-actuated striker on the receptacle to cause small soap masses extruded through the perforations in the bottom of the receptacle to be separated from the receptacle and driven off when the striker is drawn back and released.

4. A device as set forth in claim 3, in which the striker is in the form of a flap located within the receptacle and supported for swinging movements from and toward the bottom of the receptacle.

5. A device as set forth in claim 3, in which the striker is located on the outside of the receptacle and is adapted to strike blows against the side of the latter.

6. A device for producing artificial snow from soap, comprising a stiff open-top receptacle having a perforated bottom, a long flexible sleeve secured to the open end of the receptacle and constituting an extension thereof, a rigid handle secured to the receptacle and extending therefrom through the sleeve and beyond the free end of the latter, and a spring-pressed striker on the outside wall of the receptacle.

70

DAVID H. CROSHER.
